UNITED STATES PATENT OFFICE.

JEANNE A. ANDERSON, OF OMAHA, NEBRASKA.

DRAFTING-TOOL.

1,232,020.

Specification of Letters Patent. Patented Oct. 22, 1918.

Application filed May 20, 1918. Serial No. 235,723.

To all whom it may concern:

Be it known that I, JEANNE A. ANDERSON, a citizen of the United States, residing at Omaha, in the county of Douglas and State of Nebraska, have invented certain new and useful Improvements in Drafting-Tools, of which the following is a specification.

This invention relates to a drafting tool used in forming curves or circles and particularly adapted for the use of classes in drawing, manual training, kindergarten schools, or by architects, and has for its principal object to provide such a construction that it will be convenient and durable in use, and may be manufactured economically.

The invention consists of the novel construction, combination and arrangement of parts as described herein and claimed, and as illustrated in the accompanying drawing, wherein,—

Figure 1 is a view in side elevation of the drafting tool. Fig. 2 is a view of the tool, partly broken, showing the reverse side to that shown in Fig. 1. Fig. 3 is an enlarged detail relating to Fig. 1. Fig. 4 is a plan view of the socket or pencil-holder. Fig. 5 is a sectional view on line 5—5 of Fig. 4, the scale-strip being omitted. Fig. 6 is a transverse section through the sleeve on line 6—6 of Fig. 4.

Referring now to the drawing for a more particular description, I provide a strip 8 of substantially uniform width and thickness, having a slot 9 formed therein of substantially uniform width, said slot having a length nearly equal to the length of the strip, and having indices marked thereon at longitudinal intervals, as clearly shown in the drawing for indicating linear measurements, and providing a scale-strip.

At 10 is indicated a pivot-post, its upper end providing a handle *a*, said post being provided near its convergent lower end with an annular groove *b* formed between the bosses *c*, the width of the groove being substantially equal to the width of the strip 8, the latter having an end-portion *d* bent to a cylindrical form for engaging in said groove as a holding means, and it will be understood that the post may be held upright and stationary, with its tapered part upon a support or upon a paper sheet which is to be marked, and the scale-strip may have a swinging movement, the stationary post being the center of said movement.

Numerals 11 indicates a socket-member, slide or pencil-holder, consisting of a sleeve *e* provided, to project transversely from its side, with a pair of resilient, parallel plates *f* and *g*, connected at their upper edges and thereby forming a recess substantially of inverted U-shape in cross-section, for receiving the scale-strip, said plates having suitable apertures for receiving a set-screw 12, the aperture of the plate *f* having a threaded wall *h*.

As best shown in Figs. 1 and 4, the plate *g* is provided with a rectilinear wall *k*, disposed at right-angles thereto and parallel with the longitudinal axis of the sleeve, this being a matter of convenience in the use of the device.

The parts thus described may be used to great advantage for drawing curves or circles. After a pencil *m* has been disposed in the sleeve as shown in Figs. 1 and 2 it may be secured therein against longitudinal movements by the set-screw which is threaded in the wall *f*, the set-screw bearing upon the plate *g* and operating, when rotated, to cause the resilient plates to move toward each other for coincidentally compressing the pencil in the sleeve and securing the pencil-holder in stationary relation with the scale-strip.

The device, as described, may have any desired length or proportion, and in instances where a greater length than ordinary is required, the scale-strip, at its distal end, is provided with a roller or caster *n*, the pintle *p* of the caster being preferably provided and circumscribed by a spring *s* disposed in the housing or cylindrical terminal part *t* of said strip, a washer *w* being interposed between the head of the pintle and the upper end of the housing and suitably secured thereto.

The device is very convenient in use for any of the purposes mentioned. The holder 11 may be readily mounted upon the scale-strip since the plates *f* and *g* are not connected at their lower ends, and the pencil-holder may have slidable movements on the strip, the stem of the screw engaging in the slot 9. After the pencil-holder has been adjusted to a suitable distance from the post it may be secured by the means described, the advantage of the wall *k*, during said adjustment, being that it will operate as a guide for conveniently disposing the convergent end of the pencil at any prede-

terminated indice of the scale-strip; for instance, in the use of the herein described drafting-tool, it may be stated, if it is desired to mark a circle having a radius of 5 four inches, the operator slides the holder 11 outwardly from the handle until the wall *k* registers with the graduation "4," and the point of the pencil will then be disposed in a plane at a distance of four inches from 10 the lower, convergent end of the handle, and the spring *s* permits a limited downward movement of the pencil upon the drawing sheet, or other surface to be marked.

It should be stated that, for ordinary use 15 in schools, the caster is dispensed with, since comparatively short scale-strips are employed, but for describing large circles the caster is of advantage since it supports the weight of a long strip and operates as an aid 20 in applying pressure of the pencil to the paper or other surface to be marked.

What I claim as my invention is,—

In a drafting tool, a post having a convergent terminal, a graduated strip provided with a slot and arranged to swing 25

from said post, a holder-member including a pair of substantially parallel, opposed, connected plates provided at one of their ends with a curved, elongated wall for partly encircling a marking device, one of 30 said plates having a rectilinear wall connected with said curved, elongated wall and disposed at right angles to said plates substantially parallel with the longitudinal axis of said curved, elongated wall, said 35 holder-member being adapted to be disposed with its plates at opposed sides and normally to have slideable movements for adjustments longitudinally of the strip, and a set-screw disposed in the slot of said strip 40 and traversing said plates for pressing the latter against the strip and for pressing said curved, elongated wall against the marking device.

In testimony whereof I have affixed my 45 signature in presence of two witnesses.

JEANNE A. ANDERSON.
